UNITED STATES PATENT OFFICE

ALEXANDER E. SQUYARS, OF MAXTON, NORTH CAROLINA.

SWITCH.

No. 919,261.

Specification of Letters Patent.

Patented April 20, 1909.

Application filed August 18, 1908. Serial No. 449,104.

To all whom it may concern:

Be it known that I, ALEXANDER E. SQUYARS, a citizen of the United States, residing at Maxton, in the county of Robeson 5 and State of North Carolina, have invented a new and useful Switch, of which the following is a specification.

This invention relates to automatic switches for steam or electric railways and 10 has for its object to provide improved means for effecting the movement of the switch thereby to permit a train to pass onto or from a siding.

A further object of the invention is to provide a switch including depressible track devices operable by the wheels of a passing car to move the switch to open position, suitable 15 operating mechanism being provided for automatically closing the switch after the 20 passage of a train onto or from the siding.

A further object is to provide improved means for locking the depressible track devices in inoperative position, and means operable from the car for releasing the track devices thereby to permit the latter to be actuated by the car wheels for effecting the 25 movement of the switch.

A still further object of the invention is generally to improve this class of devices so 30 as to increase their utility, durability and efficiency.

Further objects and advantages will appear in the following description, it being understood that various changes in form, 35 proportions and minor details of construction may be resorted to within the scope of the appended claims.

In the accompanying drawings forming a part of this specification: Figure 1 is a plan 40 view of an automatic switch constructed in accordance with my invention showing the switch points in closed position. Fig. 2 is a similar view showing the switch points in open position. Fig. 3 is a transverse sectional view taken on the line 3—3 of Fig. 1, showing the track devices in inoperative position. Fig. 4 is a similar view showing the track devices actuated by the car wheel to effect the movement of the switch. Fig. 5 is 45 a transverse sectional view taken on the line 5—5 of Fig. 1. Fig. 6 is a detail perspective view of one end of the locking member and its associated parts. Fig. 7 is a transverse sectional view showing the manner of mounting 50 the tread piece on its depressible support.

Fig. 8 is a side elevation of the car operating mechanism.

Similar numerals of reference indicate corresponding parts in all of the figures of the drawings.

The improved switch forming the subject matter of the present invention may be used on either steam or electric railways and by way of illustration is shown in connection with a steam railway in which 5 designates 60 the main rails, 6 the siding and 7 the switch points operatively connected by a bridle bar 8, as shown.

Secured in any suitable manner to some of the cross ties 9 is a rigid bed plate 10 on 70 which is slidably mounted in suitable keepers 11 a longitudinally disposed actuating member or rod 12.

One end of the rod 12 is connected through the medium of a link 13 with the crank arm 75 14 of an operating shaft 15, the latter being mounted in suitable bearings and having its opposite ends extended longitudinally beyond the adjacent rails of the main track and provided with angularly disposed fingers 16 80 constituting tappets.

Disposed on opposite sides of the track adjacent the tappets 16 are spaced bars 17 having their upper surfaces curved downwardly 85 in opposite directions so as to assist in guiding the operating member carried by the car in engagement with said tappets, as will be more fully explained hereinafter.

The pivoted end of the actuating member or bar 12 is provided with an enlarged head 90 18 having a transverse slot 19 formed therein, one wall of which is cut away to form a locking shoulder 20.

Pivotedly mounted at 21 on the bed plate 10 are a series of levers 22 each having one 95 end thereof pivotally connected through the medium of a link 23 with the actuating bar 12; there being notches or recesses 24 formed in the bed plate at the opposite ends of the levers 22, as shown.

The notched edge of the bed plate 10 is spaced from the adjacent main rail 5, and interposed between said main rail and bed plate are one or more depressible supports or bars 25, the latter being normally and yieldably supported in horizontal alinement with the upper surface of the bed plate by suitable coiled springs 26.

Slidably mounted for lateral movement on the depressible supports 25 are tread pieces 110

27 having their lower portions formed with transverse recesses 28 adapted to receive suitable guide ribs 29 secured to the upper surface of the depressible bars 25.

5 The tread pieces 27 are operatively connected with the adjacent ends of the levers 23 by means of adjustable U-shaped pins 30, one arm of each of which is seated in a socket formed in the lower face of the adjacent tread piece while the opposite arm 31 is pivotally connected with the adjacent lever 22 and is arranged to slide within the same when the tread piece and yieldable support 25 are depressed, the notches 24 permitting 10 vertical movement of the arms 31 when the track device is actuated.

The tread pieces 27 are normally supported in inoperative position on the notched edge of the bed plate 10 so as to prevent live 20 stock from treading on the same and actuating the switch, said tread pieces being movable to operative position above the depressible bars 27 when a longitudinal pull is exerted on the actuating bar or rod 12.

25 Journalized in suitable bearings between some of the cross ties are a plurality of auxiliary rock shafts 32 each provided with a crank arm 33 and having one end thereof extended beneath the bed plate 10 and provided with an angularly disposed finger 34 which enters an adjacent eye or clip 35 secured to the bottom of the depressible bar or support 25.

30 Secured to the crank arm 33 is a chain, cable or other flexible medium 36, which latter extends around a sheave or pulley 37 and is anchored in any suitable manner to the bridle bar 8.

35 The bridle bar 8 is slidably mounted between adjacent cross ties 9 to one of which is pivotally mounted at 38 a locking dog or pawl 39 one end of which is adapted to engage the shoulders 20, while the opposite end thereof is provided with a segmental 40 notch or recess 40 for engagement with a pin 41 carried by the bridle bar, as shown.

45 A leaf spring 42 serves to normally and yieldably support the catch end of the pawl in engagement with the head 18 of the actuating member 12 so that when a longitudinal 50 pull is exerted on said member and the shoulder 20 registers with the catch end of said pawl, the latter will bear against the shoulder and thus hold the actuating member in retracted position.

55 A coiled spring 43 is fastened to a suitable support between the main rails 5 with one end thereof extended laterally and the terminal thereof bent to form an angularly disposed arm 44, which latter passes through an elongated slot or opening 45 in the bed plate 10 for attachment to the actuating bar 12, the tendency of the spring 43 being normally to support the actuating bar 12 in 60 extended position.

A stop lug 45 is rigidly secured to and movable with the bridle bar 8, said lug being adapted to bear against the adjacent end of the actuating bar 12 at the recess 19 for limiting the extensible movement of said 70 bar.

75 Mounted adjacent one of the rails of the siding 6 is an auxiliary tread piece 46 having its upper longitudinal edge normally and yieldably supported above the tread surface of the rail by suitable coiled springs 47, the lower surface of the auxiliary tread piece being arranged to bear against the adjacent crank arm 48 of a stub shaft 49.

80 The opposite crank arm 50 of the stub shaft 49 is connected with one end of a lever 51, to the other end of which is connected a cord or cable 52, which latter passes around a sheave or pulley 53 arranged above the pulley 37 and mounted for rotation in a 85 suitable bracket or casing 54, the end of the cable 52 being anchored in any suitable manner to the bridle bar 8.

80 A spring 55 is preferably interposed between one of the switch rails 7 and the 90 bracket 54 to assist in returning the switch points to closed position after the passage of a car.

95 The actuating bar and its associated parts are preferably housed in a suitable casing 95 or box 56 disposed adjacent the tread piece in order to prevent injury to said parts.

100 The mechanism carried by the car for engagement with the tappet is shown in Fig. 8 of the drawings and consists of an air cylinder 57 mounted on the engine or one of the car trucks and provided with a piston rod 58, which latter is normally and yieldably supported in retracted position by a spring 59, one end of which is secured to the journal 105 box and the opposite end thereof arranged to engage the free end of the piston rod, as shown.

110 Pivottally mounted in suitable bearings 60 on the car truck is an oscillating frame 61, 110 one end of which is bent to form a lip 62 adapted to ride up the curved faces of the guide bars 17 for engagement with the tappets 16 when said frame is moved to lowered position.

115 One end of a rope or cable 63 is secured to the frame 61 with its opposite end passing over a sheave or pulley 64 for attachment to the piston rod 58.

120 A tube or hose 65 forms a connection between one end of the cylinder and the train pipe, while the opposite end of the cylinder is provided with a suitable exhaust valve 66. Thus it will be seen that when steam is admitted to the interior of the cylinder 57 the 125 piston rod will be forced outwardly, against the tension of the spring 59, thereby allowing a certain amount of slack in the cord 63 and permitting the frame 61 to drop by gravity to lowered or operative position so as to en- 130

gage the tappet as the car travels in the direction of the switch.

The frame 61 may be locked in lowered or inoperative position by means of a lever 67, 5 one end of which is pivotally mounted on the piston rod 58 while the other end thereof is adapted to bear against the adjacent head of the cylinder.

When the supply of air or steam to the cylinder 57 is cut off and the lever 67 released the tension of the spring 59 will force the piston rod within the cylinder and through the medium of the cable 63 automatically move the frame 61 to elevated or inoperative position. 15

The operation of the switch is as follows: As the train approaches the switch the frame 61 of the car device is moved to lowered position, in the manner before stated, so that 20 when the lip 62 rides up the curved face of the guide bars 17 it will engage the adjacent tappet 16 and oscillate the shaft 15, thereby to exert a longitudinal pull on the link 13 and retract the actuating bar 12 against the 25 tension of the spring 43. As the actuating bar is retracted the levers 22 will move the tread pieces 27 from the bed plate to a position above the depressible bars 25 and in the path of movement of the wheels of the 30 passing train. When the locking bar 12 is moved rearwardly the pawl or dog 39 will engage the shoulder 20 so as to prevent further movement of the actuating bar and thus support the tread pieces 27 in position 35 to be engaged by the car wheels. When the wheels of the car engage the tread pieces the weight of the car will depress the tread pieces together with the bars 25 and through the medium of the crank arms 33 exert a 40 longitudinal pull on the cable 36, which latter being passed around the sheave 37 and attached to the bridle bar 8 will automatically move the switch points 7 to open position so as to permit the train to pass from 45 the main rails onto the siding. As the bridle 8 is actuated to open the switch the pin 41 will engage the recessed end of the pawl 39 and disengage said pawl from the shoulder 20, while at the same time the stop 50 lug 45 will bear against the adjacent end of the head 18 so as to prevent forward movement of the actuating member after the pawl 39 is released. As soon as the weight 55 of the car is relieved from the tread pieces the springs will automatically move the switch points to closed position. As the switch points are moved to closed position the lug 45 will be disengaged from the adjacent end of the head 18 thus permitting the 60 spring 43 to move the actuating bar forward or to extended position and in which position the stop lug will bear against the adjacent wall of the recess 19, as best shown in Fig. 2 of the drawing. As the train passes 65 over the siding the wheels of the car will de-

press the auxiliary tread piece 46 without affecting the movement of said switch. When the train in traveling from the siding on the main rails, the wheels of the car will depress the auxiliary tread piece 46 and 70 through the medium of the stub shaft 49 and cable 52 move the switch to open position so as to permit the passage of said train, the stop lug 45 operating within the slot 19 when the switch is moved to open position 75 from the siding.

From the foregoing description, it is thought that the construction and operation of the device will be readily understood by those skilled in the art and further description thereof is deemed unnecessary. 80

Having thus described the invention what is claimed is:

1. An automatic switch including the main rails, switch point and siding, a depressible track device operatively connected with the switch point, and movable vertically in a plane substantially parallel with the road-bed, means for locking the track device in inoperative position, and means operable by a passing train for releasing said track device and actuating the same to effect the movement of the switch points. 85

2. An automatic switch including the main rails, switch point and siding, a tappet, a depressible track device operatively connected with the tappet and switch point, respectively, and movable vertically in a plane substantially parallel with the road-bed, means for locking the track device in inoperative position, and means operable by a passing train for actuating the tappet to release the track device and effect the movement of the switch. 95

3. An automatic switch including the main rails, switch point and siding, a tappet, a depressible track device movable vertically in a plane substantially parallel with the road-bed, a connection between the track device and tappet, means for normally locking the track device in inoperative position, means operable by a passing car for moving the track device to operative position, and a connection between the track device and switch point for moving the latter to open position when the track device is operated. 105

4. An automatic switch including the main rails, switch point and siding, a depressible member operatively connected with the switch point, a tread piece movable to operative position above the depressible member, means for locking the tread piece in inoperative position, and means operable by a passing car for moving the tread piece to operative position and effecting the movement of the switch. 120

5. An automatic switch including the main rails, switch point and siding, a depressible member operatively connected with the switch point, a tread piece movable to opera- 125

tive position above the depressible member, a tappet, an actuating bar operatively connected with the tread piece and tappet, respectively, said tappet being actuated by a passing car to operate the actuating bar thereby to move the tread piece to operative position.

6. An automatic switch including the main rails, switch point and siding, a depressible member operatively connected with the switch point, a laterally movable tread piece, and means operable by a passing car for moving the tread piece in engagement with the depressible member and simultaneously actuating said tread piece to effect the movement of the switch.

7. An automatic switch including the main rails, switch point and siding, a depressible member operatively connected with the switch point, a tread piece movable to operative position above the depressible member, means for locking the tread piece in inoperative position, and means operable by a passing car for moving the tread piece to operative position and simultaneously depressing said tread piece and member for effecting the movement of the switch.

8. An automatic switch including the main rails, switch point and siding, a depressible member operatively connected with the switch point, an actuating member, a tread piece, a link connection between the tread piece and actuating member, means for supporting the tread piece in inoperative position, said tread piece being actuated by a passing train to open the switch, and means for automatically closing the switch.

9. An automatic switch including the main rails, switch point and siding, a depressible member, a tappet, a longitudinally movable actuating member operatively connected with the tappet, a tread piece movable to operative position in engagement with the depressible member, a link connection between the tread piece and actuating member, said actuating member being operable by a passing train to move the tread piece to operative position.

10. An automatic switch including the main rails, switch point and siding, a depressible member, a spring pressed actuating member, a tread piece, a link connection between the actuating member and tread piece for moving the tread piece in engagement with the depressible member when a longitudinal movement is exerted on the actuating member, said actuating member being operable by a passing train.

11. An automatic switch including the main rails, switch point and siding, a bed plate, a depressible member interposed between the bed plate and one of the main rails, a longitudinally movable actuating member, a tread piece movable to operative position

above the depressible member, a link connection between the depressible member and actuating member, means for locking the actuating member in retracted position, and means for releasing said actuating member and operating the switch when the tread piece is depressed.

12. An automatic switch including the main rails, switch point and siding, a bed plate, a longitudinally movable actuating member slidably mounted on the bed plate, a depressible member interposed between the bed plate and one of the main rails, a tread piece slidably mounted on the bed plate and movable to operative position in engagement with the depressible member, a shoulder formed on one end of the actuating member, a pawl adapted to engage the shoulder for locking the actuating member in retracted position, said pawl being movable to released position when the tread piece is depressed.

13. An automatic switch including the main rails, switch point and siding, a depressible member, a bed plate having recesses formed in one longitudinal edge thereof, a longitudinally movable actuating member, links secured to the actuating member, clips forming a pivotal connection between the links and tread piece, means for locking the actuating member in retracted position, and means operable by a passing train for depressing the tread piece and simultaneously releasing the actuating member thereby to move the switch to open position.

14. An automatic switch including the main rails, switch point and siding, a depressible member, crank shafts operatively connected with the depressible member, a flexible medium forming a connection between the crank shaft and switch point, a longitudinally movable actuating member, a tread piece movable to operative position in engagement with the depressible member, and a connection between the tread piece and actuating member, said tread piece being actuated by a passing car to effect the throwing of the switch.

15. An automatic switch including the main rails, switch point and siding, a depressible member, a longitudinally movable actuating member, a crank shaft having a tappet, a longitudinally movable operating member operatively connected with the crank shaft, a tread piece, a connection between the tread piece and actuating member, means for locking the actuating member in retracted position, and means operable from a passing train for depressing the tread piece and at the same time releasing the actuating member thereby to move the switch to open position.

16. An automatic switch including the main rails, siding and switch points, a bridle bar connecting the switch points, a depressi-

ble member, a longitudinally movable actuating member having a recess formed in one end thereof and provided with a shoulder, a tread piece movable to operative position 5 on said depressible member, a connection between the tread piece and actuating member, a pawl adapted to engage the shoulder, said tread piece being actuated by a passing train to effect the movement of the switch, 10 and a stop lug carried by the bridle bar and adapted to engage the walls of the recess in the actuating member when the latter is moved to extended position.

17. An automatic switch including the 15 main rails, siding and switch points, a bridle bar connecting the switch points, a depressible member, a bed plate, a spring pressed actuating bar slidably mounted on the bed plate and having a recess formed in one 20 end thereof, a tread piece movable to operative position on the depressible member, a connection between the tread piece and actuating member, a pawl adapted to engage the recessed end of the actuating member 25 for locking the latter in retracted position, a stop lug carried by the bridle bar for engagement with said actuating member when the latter is moved to extended position, a tappet, and a connection between the tappet and the actuating member, said tappet being operable by a passing train to move the

tread piece in engagement with the depressible member.

18. An automatic switch including the main rails, siding and switch points, a bridle 35 bar connecting the switch points and slidably mounted between the adjacent cross ties of the main rails, a bracket secured to said cross ties and embracing the bridle, pulleys journaled in the bracket, a depressible member, 40 a longitudinally movable actuating member, a tread piece movable to operative position on the depressible member, a connection between the tread piece and actuating member, a crank arm operatively connected with the depressible member, a flexible medium secured to the crank arm and passing around one of the pulleys of the bracket for attachment to the bridle bar, 45 an auxiliary depressible member, and a flexible medium operatively connected with the auxiliary depressible member and passing over the other pulley for connection with the bridle bar.

In testimony that I claim the foregoing 50 as my own, I have hereto affixed my signature in the presence of two witnesses.

ALEXANDER E. SQUYARS.
